DEVICE FOR FIXING THE OUTER END OF A
HAIRSPRING TO THE COCK OF TIME-
PIECES

Fritz Marti, La Chaux-de-Fonds, Switzerland

Application February 14, 1947, Serial No. 728,435
In Switzerland October 30, 1945Section 1, Public Law 690, August 8, 1946
Patent expires October 30, 1965

1 Claim. (Cl. 58—113)

1

In the time-pieces hitherto known, the outer end of the hair-spring is fixed to the cock by a stud. In order to modify the active length of the hair-spring a regulator curb is used, between the pins of which the hair-spring is held freely or gripped resiliently, and these pins are displaced by turning the regulator curb along the outer turn of the hair-spring. The curb has however the disadvantages of diminishing the regulating properties of the regulating device by impairing its isochronism.

An important feature of the present invention resides in that the fixing device comprises two members that grip between them the end of the hair-spring, at least one of these members being so mounted that it can be manipulated, and that when so manipulated it will enable the hair-spring to be carried along so as to modify its active length.

One embodiment of the invention is illustrated by way of example in the accompanying drawings, in which:

Figure 1 is a plan view; and

Figure 2 is a section on the line II—II in Figure 1.

In these drawings, 1 denotes the cock-plate of a time-piece regulated by a balance-wheel, 2 is an index centre-piece fixed to the cock by two screws 3, and bearing at its centre the cover-plate 4 of the upper bearing of the regulator balance-staff, the pierced stone 5 of which is inserted in an aperture in the cock. 6 denotes a Breguet hair-spring, the outer end of which is to be fixed to the cock. On the serge of the index centre-piece 2 is mounted with oiled friction a regulator curb 7, provided with a lug 8. In a thickened flange 8' of this lug is formed a radial slot-guide 9, leading to a circular milling 10. In an axial aperture in the bottom of this milling 10 is pivotally mounted a roller 11 which is rigid with a toothed pinion 12 and with a star wheel 13. The lower end of the roller 11 is provided with a collet 14 in which is formed a peripheral groove 15. In the radial slot-guide 9 is mounted a second roller 16, which is rigid with a toothed pinion 17, meshing with the pinion 12 of the first roller. The lower end of the roller 16 is provided with a collet 18, the breadth of which corresponds to that of the groove 15 of the roller 11. An approximately S-shaped spring 19, lodged in a pe-

ripheral groove 20 in the regulator curb, tends to urge the roller 16 towards the roller 11, and to keep the pinions 12 and 17 of these two rollers in mesh with one another. The outer end of the hair-spring 6 is resiliently nipped between the collet 18 of the roller 16 and the bottom of the groove 15 in the roller 11. The spring 19 is kept stressed by a pin 21.

In order to regulate the active length of the hair-spring, the outer end of which is resiliently but firmly held by the two rollers 11 and 16, which take the place of the usual stud, all that is necessary is to turn the manipulating star wheel 13 in the desired direction. In this way a movement of rotation is impressed upon the two rollers, which displace the outer turn of the hair-spring, and shorten or lengthen it according to the direction of rotation. A graduated scale is arranged around the milling 10 in which the manipulating star wheel 13 is lodged. Regulation is therefore effected not as hitherto by displacing the regulating curb relatively to the stud, but by moving the outer turn of the hair-spring by means of the rollers 11 and 16, which take the place of the stud and curb pins usually employed, the curb 7 remaining stationary.

When assembling or repairing the movement, a preliminary regulation may be effected by slightly modifying the initial angular position of the regulator curb, which position may be selected according to the configuration of the calibre, and above all the shape of the cock, in whatever way is the most practical for the manipulation of the star wheel.

The two fixing rollers might be mounted directly upon the cock, or upon a fixed piece attached to the cock. One of them might be fixed and the other rotatable. One of the rollers might be replaced by a pin.

What I claim is:

In a device for fixing the outer end of a hair spring to the cock of a time-piece, comprising a support member having a recess, two rollers provided with meshing gears and having cooperating surfaces adapted to nip the end of the hair spring therebetween, said rollers being rotatably mounted in said support with their gears on one side of the support and the said cooperating surfaces on the opposite side of said support, one of said rollers being disposed in a radial slot in

said support member and being slidable in said slot relative to the other roller, manually operable means for rotating said rollers whereby to shift the hair spring and to modify the active length thereof, and a spring disposed in said recess in said support urging said second-named roller against said first-named roller, said spring engaging said second-named roller substantially in the center of the distance between the gears and the nipping surfaces, whereby the pressure of said spring is substantially equally distributed on the gears and on the nipping surfaces.
